United States Patent Office.

THOMAS DOLAN, OF PHILADELPHIA, PENNSYLVANIA.

Design No. 4,975, dated June 6, 1871.

DESIGN FOR A STOCKING FABRIC.

The Schedule referred to in these Letters Patent and making part of the same.

I, THOMAS DOLAN, of Philadelphia, county of Philadelphia, State of Pennsylvania, have invented or produced a Design for a Stocking Fabric, of which the following is a specification.

The figure in the accompanying drawings represents my design for a stocking fabric, the main feature of which is the broad stripe A, composed of a number of plain bars and of ornamental ribs a, a¹, and a².

Above the main stripe A are two narrow stripes, B and B¹, each composed of a group of narrow bars, as shown, and below the main stripe is another narrow stripe, B², similar to B and B¹.

Between the stripes B and B¹ is a number of plain ribs, c, and below the stripe B² are similar plain ribs d.

Irrespective of the colors employed,
I claim—

1. The design for the stripe A, as shown and described.
2. The design for the entire stocking fabric, including the stripes A B B¹ B² and the ribs c and d.

In testimony whereof I have signed my name to this specification in the presence of two subscribing witnesses.

THOMAS DOLAN.
